UNITED STATES PATENT OFFICE.

WILLIAM L. MAST, OF ARTHUR, ILLINOIS.

ATTACHMENT FOR DOOR-LATCHES.

1,216,584.

Specification of Letters Patent. Patented Feb. 20, 1917.

Application filed March 25, 1916. Serial No. 86,643.

To all whom it may concern:

Be it known that I, WILLIAM L. MAST, a citizen of the United States, residing at Arthur, in the county of Douglas and State 5 of Illinois, have invented certain new and useful Improvements in Attachments for Door-Latches, of which the following is a specification.

This invention relates to attachments for 10 door latches and the primary object of the invention is to provide a supplemental crank for the latch for facilitating the opening and closing of the latch by means of a crank motion rather than the twist motion which 15 must be given to the ordinary door knob when it is desired to open or close the latch of the door.

The invention further aims to provide an 20 attachment of this character which will be constructed in a manner that will allow it to be used on any standard form of door latch; it being only necessary to remove the door knob from the latch and secure it on the end of the crank while the opposite end 25 of the crank is secured to the operating rod of the latch in a manner similar to the fastening of the door knob thereof.

A further object of this invention is the 30 provision of an attachment for door latches which consists of comparatively few parts and is simple in construction, but durable and well adapted to withstand the rough usage to which devices of this character are 35 ordinarily subjected.

For a full description of the invention and the advantages and merits thereof, reference 40 is to be had to the following description and the accompanying drawings, wherein is illustrated the preferred form of my invention, in which;

Figure 1 is a fragmentary side elevation of a portion of a door showing the attachment applied to the latch.

Fig. 2 is a perspective view of the attachment.

One of the inconveniences found in the ordinary door latch which is operated by the ordinary door knob is the difficulty of turning the knob when a person's hands are wet or when the person is carrying bundles which make it difficult to turn the knob of the door. By providing the latch with a means for opening the latch with a crank motion instead of a twist or turning motion 55 this difficulty can be greatly avoided. The door A is provided with the usual latch B

which is operated by the operating rod b which extends transversely through the door and ordinarily is operated by a knob on each side of the door. The attachment, which 60 is intended to be mounted upon the operating rod in a manner similar to the mounting of the ordinary door knob consists of the straight arms 1 and the angularly disposed socket end 2 in which the socket 3 is 65 formed, the socket being of a standard size as is found in the ends of the sockets of door knobs. The socket 3 therefore, is placed upon the end of the operating rod and the fastening screw will be inserted 70 through the aperture 4 screw threadedly mounted in the threaded apertures which are found in the ends of all standard latch operating rods. This construction, therefore, provides for the securing of the attachment in a manner exactly the same as 75 the door knob is secured when the door knob is employed.

The door knob C will be mounted upon the angularly disposed socket portion of the 80 attachment which extends at right angles from the arm 1 and is provided with the squared end 5 through which an aperture 6 extends and is provided with screw threads similar to the screw threads in the openings 85 in the operating rod of the latch. The door knob therefore, will be attached to the squared portion in the exact manner of its attachment to the operating rod of the latch.

By reference to Fig. 1 of the drawing it 90 will be seen that the full lines indicate the position of the door knob when the latch is in closed position and when the door is closed; the dotted lines indicating the position of the door knob when the latch is in 95 open position when it is desired to open the door. This motion therefore, may be accomplished by simply pressing the door knob to one side and, if the person's hands are wet or should be hampered by other 100 means it will be only necessary to place the arm against the knob to cause the knob to be pressed downwardly for opening the door. The attachment is one that may be quickly and easily applied and it is intended 105 that the socket and squared end will be constructed of standard sizes whereby it may be employed in connection with the standard size of latches and door knobs.

From the foregoing it will be observed 110 that a very simple and durable attachment for door latches has been provided, the de-

tails of which embody the preferred form. I desire it to be understood however, that slight changes or modifications in the minor details of construction may be made without departing from the spirit of the invention or the scope of the claims hereunto appended.

I claim:

1. The combination with a door and a latch for the door having an ordinary operating rod, of an operating crank provided with angularly disposed oppositely extending end portions, one of said end portions provided with a square socket for receiving said operating rod and having a fastener receiving opening formed in its side communicating with the interior of said socket, the opposite end portion of said crank provided with a reduced square stem of a size equal to the size of the square socket in the first mentioned end portion, and a knob mounted upon the square stem, the said square stem and said square operating rod being of similar formation whereby said knob may be interchanged from said operating rod and mounted upon said stem.

2. The combination with a door and a latch for the door having an ordinary square operating rod, of an operating crank adapted to have its ends interchangeably connected with said operating rod, right-angularly disposed and oppositely extending end portions formed on said crank, one of said end portions being provided with a square socket the opposite of said end portions provided with a square stem, each of said end portions provided with a fastener receiving aperture, a knob adapted to be detachably mounted on said stem or on said operating rod, the main portion of said operating crank adapted to be disposed upwardly at right angles from said operating rod, the attaching portion of said knob adapted to be received either by the end of said stem or the end of said operating rod.

In testimony whereof I affix my signature in presence of two witnesses.

WILLIAM L. MAST.
